UNITED STATES PATENT OFFICE.

EDWIN H. COLPITTS, OF EAST ORANGE, NEW JERSEY, ASSIGNOR TO WESTERN ELECTRIC COMPANY, INCORPORATED, OF NEW YORK, N. Y., A CORPORATION OF NEW YORK.

WIRELESS TELEGRAPHY AND TELEPHONY.

1,256,983.

Specification of Letters Patent. Patented Feb. 19, 1918.

Application filed January 27, 1916. Serial No. 74,576.

To all whom it may concern:

Be it known that I, EDWIN H. COLPITTS, a subject of the King of Great Britain, residing at East Orange, in the county of Essex and State of New Jersey, have invented certain new and useful Improvements in Wireless Telegraphy and Telephony, of which the following is a full, clear, concise, and exact description.

0 This invention relates to wireless telegraphy and telephony.

Its object is to provide an improved method for the simultaneous transmission of telephone and telegraph signals and for 5 their reception. This object is accomplished by transmitting telephone signals by means of a pure modulated wave (to be defined later in this specification), and by causing the telegraph signals to destroy the purity 10 of this wave.

In radio telephony it has been customary to supply to the antenna a wave of constant frequency and constant amplitude by means of a sending generator. The amplitude of 15 this wave is then modulated in accordance with the signal to be sent. Now, it is well known that when a constant amplitude wave of frequency C (carrier wave) is modulated by means of another constant amplitude 20 wave of low frequency S (signal wave) the resultant modulated wave can be considered to be made up of three waves of constant amplitudes and of frequencies C+S, C, C-S, and these waves are propagated independently through the ether to the receiving station. It will be evident that the second of 25 the above waves, which does not contain the frequency S of the modulating signal, represents a waste of power in the antenna, and it has been proposed in applications Serial 30 No. 64,502 and Serial No. 64,524, both filed December 1, 1915, to eliminate from the transmitting antenna the current of frequency C, and thereby to produce what will 35 be called hereafter a pure modulated wave. The effect of the wave of frequency C is then introduced at the receiving station by means of a local generator of that frequency. The result of this method of telephony is to 40 secure a much higher efficiency, since in practice the power represented by currents of frequency C is in general larger than the power represented by the other components.

The present invention proposes to utilize this method of telephony, and in addition 55 to restore the wave of frequency C at the transmitting station in accordance with telegraph signals to be sent, so that telephone and telegraph messages may be sent simultaneously. A telegraph key is here arranged 60 to superpose a wave of frequency C upon the outgoing signals, and thereby to destroy the purity of the modulation in accordance with the telegraph signals. At the receiving station a particular arrangement of apparatus 65 is adopted which will be more completely described in connection with the drawing.

Figure 1 represents diagrammatically a sending station, and Fig. 2 a receiving station embodying the principle of the invention. Fig. 3 is a diagrammatic view showing a modification of the circuit arrangement at the sending station.

Referring to Fig. 1, 1 is a generator of 75 constant amplitude high frequency waves, 2 is a microphone, and transformers 3 and 4 are adapted to impress both the high frequency waves generated by 1 and the low frequency modulating waves generated by 2 upon the input circuit of a thermionic modulating device 5. The effect of this arrangement is to produce in the output circuit of 80 the modulator 5 a high frequency current whose amplitude varies in accordance with the signals produced by the microphone 2. 85 The transformer 6 serves to introduce these currents into a system of tuned circuits 7 and 8, whose functions are as follows:

The branch 7 is tuned to the frequency of 90 the generator and therefore serves as a short circuit to currents of that frequency. The parallel arrangement of circuits 8 is so tuned as to offer a practically infinite impedance to currents of the generator frequency, and a low impedance to currents 95 whose frequencies differ therefrom by the frequencies occurring in speech. There will therefore exist in the windings of transformer 9 practically no current of the generator or carrier frequency represented by C 100 in the preceding discussion. This transformer 9 impresses the modulated current upon the input circuits of the amplifiers 10, whose output circuits are connected to another set of amplifiers 11 arranged to furnish 105 all the power to be radiated. These

amplifiers are finally coupled to the radiating antenna 12. It will be clear that this arrangement permits the radiation of only those waves whose frequencies differ from the frequency of the generator.

13 is a telegraph key and 14 a transformer coupled to the circuit of the generator 1. When this key is closed the current of the carrier frequency is impressed directly upon the input circuits of the amplifiers 10, and currents of carrier frequency may then flow in the antenna. The resistance 15 is inserted in the key circuit to avoid short-circuiting the amplifier 10. It may also be desirable to insert a unilateral connection, such as a thermionic amplifier, in the key circuit to avoid this. Such an arrangement is shown in Fig. 3, in which 25 represents the thermionic amplifier.

Fig. 2 represents a receiving station for use in connection with the transmitting station of Fig. 1. In this, Fig. 16 is the receiving antenna which is coupled to the system of circuits 17 and 20, of which 17 is tuned to the carrier frequency, and 20 is similar to the circuit 8 of the first figure. It will be clear that when waves of carrier frequency are incident upon the antenna 16, they will produce an effect in the circuit 17, and will therefore be impressed upon the input circuit of the detecting tube 18, whose output circuit is coupled to a suitable translating device 19. When the key 13 of Fig. 1 is closed, thereby permitting the radiation of waves of the carrier frequency, an effect will be produced in the telegraph receiving device 19. On the other hand, currents of carrier frequency cannot appear in the transformer 24, which serves to couple the antenna circuits to the input terminals of a detector 21 whose output circuit supplies the telephone receiver 23. A local generator 22 of small power capacity is also coupled to the input circuit of this detector, and its function is to supply waves of the carrier frequency, eliminated at the transmitting station. This method allows the transmission of a telephone and telegraph message upon a single wave length.

It will be clear that by this method both telephone and telegraph signals may be transmitted and received independently of one another. It will also be obvious that many other systems of circuits may be devised to accomplish this same object, and that the same may be used for transmission over wire lines instead of through space: and it is therefore desired not to limit this invention to the particular circuit arrangements shown.

What is claimed is:

1. The method of simultaneous telephony and telegraphy, which consists in transmitting telephone signals by means of pure modulated waves, destroying the purity of

said waves in accordance with telegraph signals and detecting said waves at a receiving station.

2. The method of simultaneous radio telegraphy and telephony which consists in the production of a modulated carrier wave, elimination of the carrier frequency component of said modulated wave at the transmitting station, the restoration at the transmitting station of a wave of said frequency in accordance with telegraph signals to be transmitted, and the detection of said waves at a receiving station.

3. A method of signaling which comprises producing a carrier wave, modulating such wave in accordance with speech, and eliminating portions of the carrier wave component of the modulated wave for the purpose of code signaling.

4. A method of signaling which comprises producing a carrier wave at the transmitting station, modulating such wave in accordance with signals, eliminating portions of the carrier frequency component, and separating at the receiving station the remaining portions of the carrier frequency component from the received wave.

5. A signaling system including means for producing a carrier wave, signaling means for modifying said wave, a second signaling means, and means including said second signaling means for modifying the carrier frequency component of the modulated wave.

6. A signaling system including means for producing a carrier wave, signaling means for modifying said wave, a second signaling means, and means including said second signaling means for producing in the transmitted wave a signaling component of the carrier wave frequency.

7. In a signaling system, means at the transmitting station for producing a composite wave one component of which is a pure modulated wave and another component of which is a modified carrier wave, and a receiver including means selectively responsive to said components.

8. In a signaling system, means at the transmitting station for producing a composite wave one component of which is a pure modulated wave and another of which is a modified carrier wave, a receiver including indicating means responsive to one of said components, a second indicating means, and means preventing that one of the components which is responsive to the first indicating means from reaching the second indicating means.

9. In a signaling system, a receiving circuit, means therein responsive to the carrier wave component of the received wave, a second receiving circuit associated with the first receiving circuit, means for preventing the carrier frequency component from reach-

ing said second receiving circuit, and means for combining with the wave in the second receiving circuit a wave of carrier wave frequency.

10. A system for simultaneous telegraphy and telephony comprising a transmitting station including a generator of high frequency currents, means for producing from said currents a pure modulated wave modulated in accordance with speech, means for superimposing upon said pure modulated wave a wave of the said generator frequency; and a receiving station including means for detecting said superimposed wave and means for detecting said pure modulated wave.

11. A system of simultaneous telegraphy and telephony comprising a transmitting station including a generator of high frequency currents, means for modulating said currents in accordance with speech, means for eliminating the unmodulated part of said current whereby a pure modulated wave is produced, means for superimposing upon said pure modulated wave a wave of the said generator frequency and a receiving station including means for detecting said waves.

In witness whereof, I hereunto subscribe my name this 24th day of January, A. D. 1916.

EDWIN H. COLPITTS.
